(57) **CLAIM**

The ornamental design for spectacles, as shown and described.

DESCRIPTION

1.1 is a perspective view of spectacles, showing my new design;

1.2 is a front view thereof;

1.3 is a rear view thereof;

1.4 is a right view thereof;

1.5 is a left view thereof;

1.6 is a top view thereof; and

1.7 is a bottom view thereof.

The broken lines shown in the drawings of spectacles form no part of the claimed design. The solid black elements shown in the drawings of spectacles are surface indicia and form the boundary of the claim.
